UNITED STATES PATENT OFFICE.

FREDERICK J. SCHAEFER AND EMIL BEYER, OF NEWARK, NEW JERSEY.

AIR-PUMP.

1,029,232.

Specification of Letters Patent. Patented June 11, 1912.

Application filed October 24, 1911. Serial No. 656,475.

To all whom it may concern:

Be it known that we, FREDERICK J. SCHAEFER and EMIL BEYER, citizens of the United States, residing at Newark, in the 5 county of Essex and State of New Jersey, have invented certain new and useful Improvements in Air-Pumps; and we do hereby declare the following to be a full, clear, and exact description of the invention, 10 such as will enable others skilled in the art to which it appertains to make and use the same, reference being had to the accompanying drawings, and to characters of reference marked thereon, which form a part of this 15 specification.

The invention relates, generally, to improvements in air-pumps; and, the present invention refers, more particularly, to a novel construction of pump adapted for use 20 in connection with pressure tanks, plumbers' torches, plumbers' furnaces, and similar apparatus.

The present invention has for its principal object to provide a simple and easily 25 constructed air-pump, by means of which air-pressure may be generated within a suitable receptacle, and the parts of which are of such construction and arrangement, so that the discharge-end of the pump may be 30 easily and quickly closed against the escape of the air-pressure established within and by means of the pump, when not in use.

Another object of the present invention is 35 the provision of means for holding and locking the piston-rod of the pump in its inwardly thrust position, whereby not only is the discharge-opening of the pump closed, but the piston rod is maintained within the 40 pump and out of the way, when the pump is not in use.

Other objects of the present invention, not at this time more particularly enumerated, will be clearly understood from the following detailed description of the present 45 invention.

With the various objects of the present invention in view, the said invention consists, primarily, in the novel construction of air-pump hereinafter set forth; and, further- 50 more, this invention consists in the several novel arrangements and combinations of the various devices and parts, as well as in the details of the construction thereof, all of which will be hereinafter more fully de- 55 scribed in the following specification, and then finally embodied in the clauses of the

claims which are appended to and which form an essential part of this specification.

The invention is clearly illustrated in the accompanying drawings, in which:—

Figure 1 is a vertical longitudinal section of the novel construction of air-pump made according to and embodying the principles of the present invention; Fig. 2 is a top end view of said air-pump; and Fig. 3 is a transverse section of the same, taken on line 3—3 in said Fig. 1. Fig. 4 is a detail vertical longitudinal section of the upper portion of a slightly modified construction of air-pump; and Fig. 5 is a transverse section of the same, taken on line 5—5 in said Fig. 4.

Similar characters of reference are employed in all of the said hereinabove described views, to indicate corresponding parts.

Referring now to the said drawings, the reference-character 1 indicates a complete pump embodying the principles of the present invention, the same comprising a hollow tubular body-portion or shell 2. Arranged in the bottom end of said body-portion or shell is the end-plug 3, the same being of the diameter of the inside dimensions of said body-portion or shell, so as to be received within the same. Said end-plug is provided upon its circumferential sides with an annular groove 4, into which is pressed a portion of the walls of said body-portion or shell, thus forming a retaining bead 5 in holding engagement with the said end-plug. Of course, it will be understood, however, that said end-plug may be secured in its proper relation to said body-portion or shell in many other ways, such, for example, as by means of screw-threads, solder, pins, or retaining beads, in other arrangement than here described. Said end-plug is provided at its under side with an extension or nipple-portion 6 which is formed with external screw-threads 7, by means of which said pump may be secured in proper relation to the apparatus with which it is to be used. Said end-plug is further provided with a longitudinally extending opening 8, extending through said end-plug, and its extension or nipple, and forming the discharge-orifice of said pump. The upper end of said body-portion or shell 2 is formed with screw-thread portions 9, providing external and internal screw-threads. The reference-character 10 indicates a guide-block provided

with external screw-threads 11 adapted to engage the internal screw-threads formed by the screw-thread portions 9, so as to be arranged in the upper end of said body-portion or shell 2. Said guide-block is provided with a centrally disposed hole or opening 12, and the upper surface of said guide-block is further provided with a nut or finger-piece 13, extending transversely thereof, 5 and by means of which said guide-block may be manipulated to insert it within said body-portion or shell 2, or remove the same from its connection with said body-portion or shell. The reference-character 14 indicates 10 a piston rod upon the inner end of which is a suitably formed piston-member 15, the same being retained in its connection with said piston rod by means of a suitable nut-piece 16, which screws upon the screw-threaded stud 17 with which the lower end of the piston rod is connected. Said nut-piece 16 is provided upon its lower side with a receiving socket, formed by the annular wall 18, said receiving socket being 15 adapted to receive and hold a valve-member 19, preferably made of some resilient material and adapted to be pressed against the inner end of the discharge-orifice thereof. Said valve-member 19 is retained in its receiving socket by slightly turning in the 20 marginal edges of said annular wall 18 of said nut-piece, so as to cause the same to bind upon said valve-member. Said piston-rod 14 extends upwardly through the hole or opening 12 of said guide-block 10, and secured to the upper free end of said piston rod is a combined piston-rod handle and pump-cap 21, the same being provided with an annular flange or skirt 22 which is 25 provided with internally arranged screw-threads 23 adapted to be brought into engagement with said external screw-threads formed by the screw-thread portions 9 of said body-portion or shell 2, thus closing the 30 upper end of the pump and at the same time locking said piston rod in its inwardly thrust relation to said pump, whereby said valve-member 19 is brought into closing engagement with the discharge-orifice of said 35 pump, in the manner hereinabove described. By unscrewing the said combined piston-rod handle and pump-cap 21 from its engaged relation with said screw-thread portions 9 of said body-portion or shell 2, the same may 40 be used as a handle for reciprocating the piston-member and piston rod, the latter being guided in its reciprocating movements by said guide-block 10. When said combined piston-rod handle and pump-cap 21 is 45 in this manner freed from its engagement with said body-portion or shell 2, it follows that upon lifting the piston-rod, said valve-member 19 is carried away from its closing engagement with said discharge-orifice, and 50 upon the reciprocation of the pump piston-

member by means of the said piston rod, air may be forced from the interior of the pump through the discharge-orifice thereof, in the usual manner. Said guide-block 10 not only acts as a guide for said piston rod, but also 70 as a stop limiting the upward movement of said piston-member and preventing its accidental removal from the body-portion or shell 2, during the reciprocations of the same. In order to prevent shocks and jars 75 consequent upon the striking of the piston-member against said guide-block 10, there is provided a small length of coiled spring 24 which is arranged about said piston rod above the piston-member, the same acting as 80 a shock-absorber or buffer.

The above described construction of pump provides a very neat, compact, and cheaply constructed self-locking air-pump, which may be permanently secured to an air-tank, 85 or other structure, and which is proof against the leaking of air from said tank, or other structure, when the pump is not in use.

Referring now more particularly to Figs. 4 and 5 of the drawings, there is illustrated therein a slightly modified construction of guide-block and manipulating means adapted to be used in connection with an air-pump of the same general construction as that 90 hereinabove described. The reference-character 25 indicates this guide-block which is provided with external screw-threads 26 adapted to engage the internal screw-threads formed by the screw-thread portions 9 of said body-portion or shell 2, so as to be arranged in the upper end of the latter. Said guide-block is provided with a centrally disposed hole or opening 27, through which may pass the piston rod 14. Connected with said guide-block, and extending downwardly from the under side thereof, are a pair of pins or studs 28. The top-washer 29 of the piston-member 15 is provided with a pair of perforations 30 providing receiving sockets into which the ends of said pins or studs 28 enter when said piston member is drawn upwardly to the top of the body-portion or shell 2. When said pins or studs 28 are so engaged, the 100 piston rod 14 may be rotated, and such movement is transmitted to said guide-block, so that the same may be unscrewed from or screwed into the proper engagement with the internal screw-threads formed by 105 said screw-thread portions 9 of the body-portion or shell 2, whereby said guide-block is manipulated to remove the same from, or engage the same with the top of said body-portion or shell 2. When 110 we are aware that changes may be made in the various arrangements and combinations of the several devices and parts, and in the features of our present invention without departing from the scope thereof, 115 120 125 130

as described in the foregoing specification, and as defined in the clauses of the claims which are appended thereto. Hence, we do not limit our invention to the exact arrangements and combinations of the various devices and parts as herein set forth, and as illustrated in the accompanying drawings, nor do we confine ourselves to the exact details of the construction of the said parts.

We claim:

1. In a pump, the combination with a tubular body-portion or shell, of screw-thread portions formed at the upper portion or mouth of said body-portion or shell to provide external and internal screw-threaded surfaces, a guide-block provided with a central opening and external screw-threads engaging said internal screw-thread surfaces of said body-portion or shell, a piston rod adapted to be reciprocated through said guide-block, and a piston-rod handle provided with an internally screw-threaded annular flange or skirt adapted to be brought into engagement with said external screw-thread surfaces of said body-portion or shell, to lock said piston-rod in its downwardly thrust position within said pump.
2. In a pump, the combination with a tubular body-portion or shell, of screw-thread portions formed at the upper portion or mouth of said body-portion or shell to provide external and internal screw-thread

surfaces, a bottom-plug provided with a discharge-orifice connected with the lower end 35 of said body-portion or shell, a guide-block provided with a central opening and external screw-threads engaging said internal screw-thread surfaces of said body-portion or shell, a piston-rod adapted to be reciprocated through said guide-block, and a combined piston rod handle and pump-cap secured to the upper end of said piston-rod, the same being provided with an internally 40 screw-threaded annular flange or skirt 45 adapted to be brought into engagement with said external screw-thread surface of said body-portion or shell, to close the top of said pump and to lock said piston-rod in its downwardly thrust position within said 50 pump when not in use, a resilient valve-member, and means connected with the inner end of said piston-rod for carrying the same, said valve-member being adapted to close the discharge-orifice of said bottom-plug when said piston rod is locked in its 55 downwardly thrust position.

In testimony, that we claim the invention set forth above we have hereunto set our hands this 13th day of October, 1911.

FREDERICK J. SCHAEFER.
EMIL BEYER.
